(57) **CLAIM**

The ornamental design for a vehicle seat protector, as shown and described.

DESCRIPTION

FIG. 1 is a three-dimensional view generally from the top left front of a vehicle seat protector embodying the invention, which is laid out flat;

FIG. 2 is a top plan view thereof;

FIG. 3 is an underside view thereof;

FIG. 4 is a left side elevational view thereof;

FIG. 5 is a right side elevational view thereof;

FIG. 6 is a lower end elevational view thereof; and,

FIG. 7 is an upper end elevational view thereof.
